UNITED STATES PATENT OFFICE.

WILLIAM SEDGWICK, OF NEWTON, IOWA.

DESIGN FOR A MENU AND CHANDELIER STAND.

42,955.

Specification for Design.

Patented Aug. 27, 1912.

Application filed April 15, 1912. Serial No. 690,830. Term of patent 7 years.

To all whom it may concern:

Be it known that I, WILLIAM SEDGWICK, a citizen of the United States, residing at Newton, in the county of Jasper and State of Iowa, have invented a new, original, and ornamental Design for Menu and Chandelier Stands, designed for use on tables and counters, of which the following is a specification, reference being had to the accompanying drawing, forming a part thereof.

The figure is a side elevation view of a stand showing my new design.

This invention relates to a new and original design for menu cards or chandeliers for use on tables, counters, and the like, and it consists, generally stated, in a structure having a square base, concave walls, and an ornamental top and base.

In the drawings 10 designates the base, which is substantially square. The body portion consists of four concave walls 11, provided with notches 12 at each corner, and the top and bottom of the body portion is ornamented by a molding 13.

I claim:

The ornamental design for a menu and chandelier stand as shown and described.

In testimony whereof I hereunto affix my signature in the presence of two witnesses, this 9th day of April, 1912.

WILLIAM SEDGWICK.
